DUAL PORT REGULATING VALVE

Myron J. Dikeman, Grosse Pointe Woods, Mich.

Original application January 5, 1949, Serial No. 69,350.
Divided and this application July 22, 1950, Serial No.
175,399

5 Claims. (Cl. 137—628)

My invention relates to a fluid control regulating valve and is a continuation in part, and division of, my former patent application Serial Number 69,350, filed January 5, 1949, now Reissue Patent No. 23,342, and is especially adapted for use therewith.

The object of my invention is to produce a divided fluid regulating valve that will function for adjoining dual port openings, either jointly or severally, and by single operating mechanism.

Another object is to produce a dual port regulating valve that may be mechanically operated for one port, and automatically operated for the adjoining port, and for chosen predetermined positions.

A further object is to provide a divided spring valve for opening adjoining ports simultaneously at predetermined sections, and automatically release and close one valve section at any chosen predetermined position, and without effecting the opposite valve operation.

A still further object is to produce a divided spring valve for dual port regulation, that is simple in construction, easily and efficiently operated and that can be manufactured at a very low cost.

These several objects are attained in the preferred form by the construction and arrangement of parts as are more fully hereinafter set forth.

Fig. 1 is an elevation of the assembled valve as mounted on the side wall of a special fluid drive and control unit casing, showing the general arrangement of the operating parts when both valve sections are in their closed positions.

Fig. 2 is a vertical sectional view as taken on the line 2-2 of the Fig. 1, showing the relative position of the dual valve sections and their respective fluid port openings.

Fig. 3 is a horizontal cross-sectional view as taken on the line 3—3 of the Fig. 1, showing the position of the dual ports, and the connecting operating ratchet means.

Fig. 4 is a vertical sectional view taken on the line 4-4 of the Fig. 1, showing the automatic valve lock and release ratchet mechanism.

Figs. 5 and 6 are cross-sectional views as taken on the line 5—5 of the Fig. 3, showing the splined drive means, and illustrates the closed, and the open positions of the valve lock and release ratchets, and means for operating same.

Fig. 7 is also an elevation the same as shown in the Fig. 1, but showing the port valve sections in their extreme open positions, and the complete fluid flow through both ports.

Fig. 8 is a vertical sectional view, similar to the Fig. 2, also as taken on the line 2—2 of the Fig. 1, illustrating a simplified modification of valve hub design, with the lock and release ratchet unit omitted.

Fig. 9 is a cross-sectional view as taken on the line 9—9 of the Fig. 8, showing the rocker arm as fixedly keyed to the bearing hub.

In general, the divided valve is designed for adjacent internal, and external, fluid channel ports within a power casing, positioned at right angles to each other, and comprise dual valve sections assembled one within the other, pivoted together, and both mounted on a common support pivot, each section designed with a closing valve surface positioned for its respective fluid port opening, the operating mechanism being connected to the inner

2

valve section and continued to the outer valve section by intervening drive ratchet means.

The dual valve is especially for controlling the fluid intake flow entering a connected gear fluid transmission unit as illustrated in my prior patent mentioned, the outer port 16 leading from the transmission reserve fluid storage chamber, for instant refilling therefrom when starting operation, then closing; while the inner port channel 41 remains open for continued internal recirculation through the connected gear transmission unit until later closed by operator.

I will now describe more fully the detailed construction of my divided dual port valve, referring to the drawings and the marks thereon.

As herein illustrated, the outer flanged valve 44 is mounted over the external channel port 16, while the inner wing valve section 44a is positioned to engage and operate the internal channel port 41, both valve sections being pivoted together and rotatably mounted over a common pivot shaft 1 fixedly mounted on the outer wall of a control casing A and adjacent to the external port 16, as is illustrated in the Fig. 1 of the drawings.

The inner wing valve section 44a is formed of a flat arm plate *a*, having a turned bearing hub *b* fixedly projected from one end thereof, at right angles thereto, said hub having a concentric shaft bearing therethrough for rotatably mounting on the pivot shaft 1, the arm plate being also designed with a curved wing valve plate *c* projected from the opposite plate end positioned to engage and fit the casing internal channel port 41. The outer valve section 44 is formed as an elongated flanged recess plate with oval ends, and with a circular bearing *d* through one end thereof, concentric with the oval end flange and designed for rotatably mounting over the inner valve plate bearing hub *b* and inclosing both said inner valve section 44a and the casing exterior channel port 16. The valve flanged edge *e* is milled to a true surface for forming a perfect pressure joint with the port 16 outer wall surface, and is retained in contact therewith by a suitable plate valve slide 5, designed and mounted to inclose the valve flanged edges when in its closed position, and is rigidly retained on the casing walls by screws 6, or other suitable means, allowing both valve sections to rotate on the common pivot shaft 1 for complete valve operation, either jointly or severally, and as illustrated in the Figs. 1 and 7 of the drawings. The plate valve slide may be extended, if desired, to encircle the entire valve flanged edge when high fluid back pressure may require more rigid valve support. The valve

section 44 is retained in its closed position, when unrestrained, by the stressed exterior spring 2 as mounted on the casing A wall, and the interior valve section 44a is retained in its closed position, when unrestrained, by the stressed intervening spring 3 as mounted between the recessed valve section edges, and as illustrated in the Fig. 3 of the drawings. Mounted over the inner valve section bearing hub *b* is a rocker arm 4, splined to the hub section by the key 7 movable sidewise in an enlarged keyway 8, designed for rotating and opening the inner valve section 44a when operating pressure is applied thereto through the connecting operating rod 45, normally when applied to an automobile fluid drive and control unit casing, would be the foot operating pedal, and reacts against a pressure return spring 9 which automatically closes both valve sections 44 and 44a when released. Also pivotally mounted within the arm plate

released. Also pivotally mounted within the arm plate **a** of the inner valve section **44a** is a special drive ratchet **10** designed for engaging a ratchet recess **11** as formed within the valve **44** wall, when both valve sections are in their closed positions, by reaction of a ratchet spring **12**, for opening both valve sections **44** and **44a** together, when an operating force is applied to the connected rocker arm **4**. The position of the ratchet recess **11** may be varied along the line of travel, as indicated by recess **11a**, in the Fig. 1, to allow any partial, or any predetermined movement of valve section **44a** before engaging the outer valve section **44** for opening operation, or for operating the internal port **41** without opening the exterior port **16**. The outer valve **44**, when engaged by the drive ratchet **10**, will continue opening the port **16** to any predetermined position, and until the drive ratchet

arm end *f* engages the opposite port channel wall and releases same from the ratchet recess *11*, automatically allowing the outer valve section *44* to close over port *16* by reaction of the stressed closing spring *2*. The length of the ratchet arm *f* may be varied, as desired, as indicated by dotted line, in Fig. 3, for timed releasing the outer valve section *44* at any predetermined position during the opening stroke. The exterior valve spring *2* must be stronger than the interior valve spring *3* to insure the full closing of both valve sections. When high back pressure is involved within the casing channel circuits, the inner wing valve section *44a* may require special valve locking means, and a dual lock-release ratchet *13* is pivotally mounted on the flanged head *g* of the pivot shaft *1*, by the pivot bearing pin *14*, designed and positioned within the pin head recess *h*, with the lock ratchet arm *k* engaged within the valve hub *b* tooth recess *15* for the valve closed position, thus rigidly restraining any valve *44a* movement when so locked. The opposite release ratchet arm *m* being positioned to engage an adjacent lifting cam *26* fixedly mounted on the rocker arm hub *4*, designed for the free splined arm movement within the key recess *8*, for lifting the lock-release ratchet clear from the hub tooth recess *15* before the valve rotation is commenced by the engaging key *7*. The lock-release ratchet is restrained in its closed position by an engaging stressed spring *17* mounted thereon, or by any other suitable means.

When low casing fluid pressure is involved, the lock-release ratchet *13* may be omitted, and the rocker arm *4* fixedly keyed directly to the inner valve section bearing hub *b*, and without the extended keyway *8*, and as illustrated in the Figs. 8 and 9 of the drawings. The dual valve operation is exactly the same as in the former case, and the valve sections are securely retained in their closed positions by reaction of the operating rod spring *9*.

It is pointed out that both the ratchet and the spring means as herein disclosed, are illustrative of any suitable substitute type of spring, or engaging units, as may be substituted therefor, also the valve drive ratchet *10* may be substituted for suitable locking or driving units, such as a pivoted lock bar *18* also operated from the lift cam *26*, or similar units as desired, as indicated by the dotted lines in the Fig. 5.

Having fully described my dual port regulating valve, what I claim as my invention and desire to secure by Letters Patent is:

1. A dual port regulating valve adapted for adjacent fluid channel ports at right angles to each other within a fluid control casing, for partially opening both valves simultaneously and then release one for instant closing, and used therewith, comprising dual adjacent inner and outer valve sections pivotally joined together at one end thereof by a bearing unit fixedly attached to one valve section, a valve operating arm mounted on said bearing unit, a common pivot shaft rotatably mounted through said bearing unit for mounting same on a casing wall adjacent one of said ports, closing spring means mounted thereon for engaging and closing each valve separately when released, each of said valve sections being formed with a valve port contact surface designed and positioned to engage and close the respective channel ports, intervening drive ratchet means mounted on one valve, engageable with the opposite valve, for operating both of said valve sections simultaneously, and trip means mounted on said ratchet for releasing the other valve at a predetermined open valve position, for instant closing of same by the closing spring reaction.

2. A dual regulating valve adapted for adjacent fluid channel ports at right angles to each other within an operating fluid casing, for partially opening both valves simultaneously and then release one for instant closing, and used therewith, comprising dual adjacent inner and outer plate valve sections pivotally joined together at one end thereof by a bearing hub fixedly mounted on the inner plate valve section integral therewith, a valve operating arm mounted on said bearing hub, a common pivot shaft rotatably mounted through said bearing hub designed to fixedly attach to a casing wall adjacent one of said channel ports, closing spring means mounted thereon for engaging and closing each valve separately when released, each of said plate valve sections being designed and positioned to engage and close one of said port openings, intervening ratchet drive means mounted on the inner valve, engageable with the outer valve, for

automatically connecting both valve sections together when closed, for partially opening said valve sections simultaneously, and a trip arm mounted on said ratchet for releasing the outer valve at a predetermined valve position for instant closing of same by the closing spring reaction.

3. A divided port regulating valve adapted for adjacent fluid channel ports at right angles to each other within an operating fluid casing, for partially opening both valves simultaneously and then release one for instant closing, and used therewith, comprising outer and inner plate valve sections assembled one within the other and pivotally joined together at one end by a bearing hub projected from the inner valve section integral therewith, and rotatably mounted through the outer flanged valve section end, each of said valve sections being designed and positioned to engage and close one of the respective adjacent casing fluid ports when valve operating pressure is released, a pivot shaft rotatably mounted through said bearing hub for fixedly attaching to a casing wall adjacent one of said ports, spring ratchet drive and release means mounted on the inner valve section positioned engageable with the outer valve section wall when both valves are closed, for partially opening said dual valves simultaneously, and ratchet trip means for releasing said outer valve at a predetermined open position for instantly closing same, an operating rocker arm mounted on said bearing hub for rotating same, spring means mounted on each valve section for returning said valves and connected mechanism to their respective closed positions when the respective valve operating pressures are released.

4. A dual port regulating valve adapted for adjacent fluid channel ports positioned at right angles to each other within a fluid operating casing, for partially opening both valves simultaneously and then release one for instant closing, and used therewith, comprising an oval flanged outer plate valve section with end bearing opening, and an inner narrow plate valve section with an end bearing hub, assembled one within the other and pivotally joined together at one end thereof by the bearing hub on the inner plate valve section rotatably mounted through the outer flanged valve section end bearing opening, each of said valve sections being designed and positioned to engage and close one of the respective casing fluid ports when valve operating pressure is released, a pivot shaft rotatably mounted through said bearing hub for mounting same on a casing wall adjacent one port, spring engaging ratchet means mounted on the inner valve section positioned to engage the outer flanged valve section, for partially opening said dual valves simultaneously, ratchet trip means for releasing said ratchet from the outer valve at a predetermined position, for instant closing of same, an operating rocker arm loosely mounted over said bearing hub and splined thereto within a widened keyway, allowing free sidewise movement before rotation engagement with the inner valve section hub, lock and release means mounted on the casing wall adjacent the inner valve section hub, engageable therewith for rigidly retaining said valve in a locked closed position, and release same, and spring means mounted thereon for engaging and returning both of said valve sections to their respective closed positions when valve operating pressure is released.

5. A dual port regulating valve adapted for adjacent fluid channel ports positioned at right angles to each other within a fluid operating casing, for partially opening both valves simultaneously and then release one for instant closing, and used therewith, comprising a flanged outer plate valve section formed with end bearing opening, and a narrow inner plate valve section formed with a bearing hub at one end thereof, both sections being assembled one within the other and pivotally joined together with said bearing hub projected through said outer valve section end bearing opening, each of said valve sections being designed and positioned at their free ends, to engage, fit, and close one of the respective casing channel fluid port openings when valve operative pressure is released, a pivot shaft rotatably mounted through said bearing hub for mounting same on the casing wall adjacent one of said ports, spring operated ratchet means mounted on the inner plate valve section designed and positioned to engage the flanged outer valve section when both valves are closed, for partially opening said dual valves simultaneously, ratchet trip means mounted thereon for releasing said ratchet from the outer valve at a

predetermined position, for instant closing of same, an operating rocker arm loosely mounted over the inner valve bearing hub and splined thereto within a wide keyway for predetermined free sidewise movement before engagement for bearing hub operation, ratchet lock and release means rotatably mounted on the casing adjacent said bearing hub, engageable with said hub for rigidly retaining said inner valve section in its closed port position, cam release means mounted on said rocker arm designed and positioned to engage said ratchet lock and release means, for disengaging same from said bearing hub during its free movement, spring means mounted on

5 said valves for engaging and returning each valve section separately to their respective closed positions when the valve operative pressure is released, and power operating means for engaging and operatively displacing said rocker arm and the attached dual valve mechanism.
